DISPENSING MACHINE VALVE

Charles Schmutzer, Irvington, N. J., assignor to
Hoffman Beverage Company, Newark, N. J., a
corporation of New Jersey

Application November 14, 1933, Serial No. 697,946

11 Claims. (Cl. 226—122)

This invention relates to valves, and has particular reference to valves for machines which dispense liquids under pressure, although it is not limited to this use.

5 In such machines as generally constructed for dispensing liquid to bottles, the empty bottle is elevated in alignment with a valve-closed dispensing tube which is accordingly inserted into the bottle a predetermined distance when a valve lifter on the tube is moved by the bottle mouth into engagement with an air valve, which is accordingly actuated to admit compressed air to a diaphragm motor operatively connected to the tube valve for opening the latter to admit the 10 liquid to the bottle from the storage tank. The air valve body is rigidly connected to the air supply pipe, and when it is necessary to clean the valve or to replace worn parts, as is frequently the case, the air pipe must be disconnected from the valve before the latter can be 15 unscrewed from the body of the dispenser to gain access to the valve, which, even then, is not readily accessible. The laborious and time-consuming task of cleaning the considerable number of dispensing valves with which each machine 20 is equipped, requires the use of wrenches and other tools, and results in the loss of service of the machine for a period of time out of all proportion to the nature of the work required.

25 In accordance with the present invention, a novel valve for liquid-dispensing machines is provided, which can be readily taken apart for cleaning without disconnecting or otherwise disturbing the air pipe connection thereto, or making it necessary to disconnect the valve body from the dispenser on which it is mounted, it being only necessary to remove the valve-packing gasket, and give the valve a quarter-turn to release it for 30 cleaning and repairing, and this is done by hand without requiring any tools.

More particularly, the new valve of this invention comprises a valve body which may be more or less permanently secured to the dispenser, and also more or less permanently connected to the air supply pipe. The interior of the body is provided with an elongated opening forming valve seat flanges, one of which has a passage connecting the interior of the valve body with the air supply pipe. The valve is T-shaped and its elongated head is adapted to fit within the elongated valve body opening and, when given a quarter-turn, to rest upon the valve seat flange in the valve body to close the air passage, rubber or other plugs being provided on the valve head for sealing the passage and being pressed tightly

against the valve seat by a spring behind the valve. The prongs of a U-shaped keeper project into the valve body at either side of the head and keep the valve from turning, this keeper being held in place by a screw ring on the valve body, which also holds the valve packing gasket. 5

Accordingly, the valve need only be turned a quarter-turn to disengage the head thereof from the valve seat flanges and to align it with the elongated valve body opening to release it after 10 the screw ring has been released. The valve is restored by reversing this procedure, and may be rapidly and simply released or replaced in a moment by simple wrist movements which include neither disconnection of the air supply pipe, nor 15 the use of tools.

For a more complete understanding of the invention, reference may be had to the accompanying drawing, in which,

Figure 1 is an elevation of a dispenser for carbonated water or other liquid, embodying the new valve of this invention; 20

Figure 2 is an axial section through the new valve in closed position, as seen along the line 2—2 of Figure 1; 25

Figure 3 is a similar view illustrating the valve in open position;

Figure 4 is a transverse section as seen along the line 4—4 of Figure 2;

Figure 5 is an axial section at right angles to the section of Figure 2, as seen along the line 5—5 of Figure 4; 30

Figure 6 is a transverse section through the valve at its seat, as seen along the line 6—6 of Figure 2;

Figure 7 illustrates the manner in which the valve is taken apart, and

Figure 8 illustrates the new air valve of this invention.

In the drawing, numeral 20 designates the bottom of the storage tank for the carbonated beverage under pressure, or other liquid which is to be dispensed to bottles or other containers. Seated within an opening in the bottom of storage tank 20 over a sealing gasket 21, is the dispenser 22 which is of more or less standard construction, including a base 23 having upwardly extending rods 24, at least one of which is pierced with an air passage 25 which communicates with a diaphragm motor 26 of standard construction having connected to its diaphragm a depending rod 27 which passes downwardly through the dispensing tube 28 extending below the bottom of the tank 20. The rod 27 is connected at its lower end to a valve 29 which normally closes the 40 45 50 55

lower end of the dispensing tube 28, being held closed by air pressure, and being unseated by the downward movement of the diaphragm motor 26 when compressed air is admitted thereto. The motion of the motor 26 is communicated to the liquid valve 29 by rod 27, and the valve opens to permit the liquid to flow from the tank 20 into the bottle.

Slidably mounted on the dispensing tube 28 is a valve lifter 30 adapted to be raised by the mouth of a bottle elevated in alignment with the dispensing tube 28 by mechanism, not shown, so that the tube 28 projects into the bottle and the valve lifter 30 raises the stem 31 to actuate the air valve, which accordingly admits compressed air from air supply pipe 32 to the diaphragm motor 26 through air valve body 33 and air passage 25 to open liquid valve 29 in the manner described.

As was previously mentioned, the air valve within the air valve body 33 is practically inaccessible in dispensing machines of standard construction, and access thereto can only be gained by disconnecting air supply pipe 32 and unscrewing the various parts of the air valve mechanism by means of wrenches and other tools and with a considerable expenditure of labor and time.

In the arrangement of the present invention, the new air valve, to all outward appearances, resembles the arrangement of standard machines so that only a few additional parts are necessary to convert the standard dispensing machine into the arrangement of this invention. For example, the base 23 of the dispenser 22 is utilized without change, as is illustrated in Fig. 2, as are the dispensing tube 28, the coupling ring 34, the gasket 35 which seals the joint between the base 23 and the valve body 33, as well as the valve packing gasket 36, the screw ring 37, and other lesser parts of the dispenser.

Instead of the usual circular opening within the valve body 33, the latter is provided with an elongated opening formed by valve seat flanges 38, one of which is pierced with an air opening 39 which communicates with the nipple 40 to which the compressed air supply pipe 32 is connected. The usual mushroom air valve is replaced by a T-shaped valve 41 having an elongated head 42 connected to the tubular valve stem 31 and adapted to fit within the elongated opening of the valve body 33 which is formed by the valve seat flanges 38, in the manner described. The opposite arms of the elongated head 42 of the air valve 41 are provided with rubber sealing plugs 43, one of which normally closes the air passage 39 as the plug 43 engages corresponding valve seat flange 38. Two plugs 43 are provided so that it is impossible to insert the valve incorrectly; that is to say, when the valve is seated within the valve body 33, one of the plugs 43 will always close the air passage 39. The light spring 44 engages the head 42 of the valve 41 and urges the plugs 43 air-tightly against the valve seat flanges 38. In order to engage the rubber plugs 43 with the valve seat flanges 38, it is necessary to give the valve 41 a quarter-turn after the head 42 thereof has been inserted in the elongated passage within the valve body 33.

The valve 42 is held against turning and is properly centered with respect to the valve seat flanges 38 by a U-shaped keeper 45, shown especially in Figs. 4, 5, and 6, and including the ring-shaped base 46 having the upwardly projecting arms 47 which fit closely against the lateral sides of the valve head 42, in the manner illus-

trated especially in Fig. 4, so that the valve head 42 is locked within the valve body 33 in the proper position. Assembly of the valve is completed by the insertion of the valve packing gasket 36 and the screwing home of the screw-ring 37.

In operation, the air valve of this invention functions precisely as the standard air valve, in response to actuation by the valve lifter 30 which engages valve stem 31 to unseat the valve head 42 from the valve seat flanges 38 and open the air passage 39 to permit the compressed air to pass the valve and then flow through passage 25 to the diaphragm motor 26 for unseating filling tube valve 29 to permit the liquid from storage tank 20 to flow downwardly through filling tube 28 into the bottle or other receptacle which actuated valve lifter 30 in the usual way.

In order to disassemble the valve for cleaning or repair, it is only necessary to unscrew screw-ring 37 to release valve-packing gasket 36 and keeper 45. Then the projecting stem 31 of air-valve 41 is grasped and given a quarter-turn to align the valve head 42 with the elongated opening of valve body 33, whereupon the spring 44 forces the valve 41 outwardly without further manipulation. These few movements may be performed with one hand and without requiring tools of any kind. The removed valve may then be cleaned or repaired, or parts such as rubber plugs 43 replaced, and the like. To restore the valve to its normal position, it is only necessary to reverse the process which is done by inserting valve 41 into the valve body 33 with its elongated head 42 in alignment with the elongated opening in the valve body 33 and then giving the valve a quarter-turn to seat it on the valve seat flanges 38. Insertion of the keeper 45 properly centers the valve 41 and prevents it from turning. Replacement of the valve-packing gasket 36 and the screw-ring 37 completes the simple act of assembling the air valve of this invention.

It will be seen that, in addition to the advantages of ready and rapid manual assembly and disassembly of the new valve, rubber plugs 43 of relatively small surface close the air passage 39 under relatively light spring pressure, insuring a tight seat at all times, as compared to the ring-shaped seat of the standard valve which may not provide a continuous seal at all times, especially when it becomes worn.

Although the valve has been illustrated and described as applied to a machine for dispensing liquids under pressure, such as carbonated water, it may be used with equal facility for dispensing fruit juices, beer, syrups, and the like, the ingredients of which, especially the pulp in fruit juices, are likely to clog the valve. In the new arrangement, the clogging particles of fruit juices and sticky syrups may be readily cleaned from the valve after each batch run. Also the valve may be changed to suit various requirements within the scope of this invention.

I claim:

1. In a device of the character described, the combination of a valve body having an elongated opening, seats at either lateral side of the opening, at least one of which has a passage, and a valve having an elongated head resting with its ends on the seats to close said passage, said valve being emplaced by inserting the head thereof through the elongated opening and then giving it a partial turn.

2. In a device of the character described, the combination of a valve body having spaced seats, at least one of which has a passage, and a valve

having a greater length but being narrower in width than the spacing between the seats and resting thereon, said valve being emplaced on the seats by inserting its narrower portion between the seats and giving it a partial turn to engage the ends thereof on the seats.

3. In a device of the character described, the combination of a valve body having an opening, spaced seats at opposite sides of said opening, at least one of which has a passage, a valve in the opening including lateral extensions resting on the seats, and spaced sealing elements on the extensions for sealing the connection between the seats and the corresponding extensions.

15 4. In a device of the character described, the combination of a valve body having spaced seats, at least one of which has a passage, a T-shaped valve having its elongated head fitting between the seats and rotatable a partial turn to engage the same, and means engaging at least one side 20 of said head to lock it against turning.

5. In a device of the character described, the combination of a valve body having spaced seats, at least one of which has a passage, a T-shaped 25 valve having its elongated head fitting between the seats and rotatable a partial turn to engage the same, and a keeper engaging the head of the valve to lock it against turning.

6. In a device of the character described, the combination of a valve body having spaced seats, at least one of which has a passage, a T-shaped valve having its elongated head fitting between the seats and rotatable a partial turn to engage the same, and a keeper insertible in the spaces 35 between the seats and the head of the valve to lock the latter against turning.

7. In a device of the character described, the combination of a valve body having spaced seats, at least one of which has a passage, a T-shaped 40 valve having its elongated head fitting between the seats and rotatable a partial turn to engage the same, and a U-shaped keeper spanning the head of the valve to lock the latter in place.

8. In a device of the character described, the combination of a valve body having spaced seats, at least one of which has a passage, a filling tube extending through the valve body, a T-shaped valve slidable thereon and rotatable a partial turn to engage the seats, a keeper on the tube for locking the valve against turning, and means for holding the keeper in position relatively to the valve.

9. In a device of the character described, the combination of a valve body having spaced seats, at least one of which has a passage, a filling tube 10 extending through the valve body, a T-shaped valve slidable thereon and rotatable a partial turn to engage the seats, spaced sealing elements on the valve engaging the seats and a spring engaging 15 the valve for urging the sealing elements against the seats.

10. In a device of the character described, the combination of a valve body having spaced seats, at least one of which has a passage, a T-shaped 20 valve insertible between the seats and emplaced thereon by giving the valve a partial turn, a filling tube extending through the valve body and valve, a removable U-shaped keeper on the valve with its prongs engaging the head thereof to lock 25 it with respect to the seats, and a source of fluid pressure communicating with the valve passage and controlled by the valve.

11. In a device of the character described, the combination of a valve body having spaced seats, at least one of which has a passage, a filling tube 30 passing through the valve body, a T-shaped valve slidable on the tube and resting on the seats with the ends of its head, said valve being emplaced on the seats by giving it a partial turn after insertion of the head thereof between the seats, spaced sealing means between the ends of the 35 valve head and the corresponding seats, a spring urging the valve head against the seats, and a source of fluid pressure connected to the passage and controlled by the valve.

CHARLES SCHMUTZER.
